UNITED STATES PATENT OFFICE.

ANNA SOLOMON, OF NEW YORK, N. Y., ASSIGNOR OF ONE-HALF TO FANNY SHAPIRO,
OF NEW YORK, N. Y.

VENTILATED HAT.

Application filed July 21, 1923. Serial No. 652,951.

To all whom it may concern:

Be it known that I, ANNA SOLOMON, a citizen of the United States, and resident of the borough of Bronx, city and State of New York, have invented certain new and useful Improvements in Ventilated Hats, of which the following is a specification.

This invention relates to ventilated hats, and has for its particular object to provide a hat of very simple construction and pleasing appearance, and which is so constructed that when the user uses the hat or cap it will not be immediately evident that such improved hat or cap differs in any way from the ordinary unventilated hat or cap. More particularly, the invention provides a hat having ventilating openings therein and provided with a foraminated band over the openings, to which may be added a foraminated stiffening member and a sweat-band provided with ventilating openings.

For this purpose, my invention consists in the novel features hereinafter described and shown in the drawings, and finally pointed out in the claims.

In the drawings:

Fig. 1 shows a front view of my improved hat embodying my invention;

Fig. 2 is a central section thereof;

Fig. 3 is a section on line 3—3 of Fig. 2;

Fig. 4 is an enlarged view of a portion of the section shown in Fig. 2.

Fig. 5 shows a modified form of ventilated hat also in accordance with my invention; and

Fig. 6 shows a detail view thereof.

Similar numerals of reference indicate similar parts throughout the several views.

Referring to the drawings, and more particularly to Fig. 1, the hat 10 has its crown and brim of the ordinary form and construction with, however, ventilating openings and with the ribbon 11 made of a special construction as will hereinafter appear.

The crown of the hat is provided with one or more large sized openings, and in the embodiment shown, preferably four in number are provided which are indicated by the numeral 13. These large sized openings in the crown of the hat act as ventilating openings.

Within the crown of the hat the leather sweat-band 14 is provided in the well known manner, but with one or more large sized openings 15 corresponding in general shape

to the openings 13 excepting that the openings 15 are slightly smaller than the openings 13, so that the contour of the sweat-band openings 15 will cover up the edges of the cut-out portions of the straw hat. 60 Preferably the openings are of elongated oval shape.

Exterior of the ventilating openings in the crown of the hat there is arranged a band of buckram or mesh, indicated by 16, 65 and having a multiplicity of openings, and this material has a certain stiffness so as to give the exterior of the hat an even circumferential contour since, if this would not have a sufficient stiffness, the hat-band 70 would press into the hat openings 13 and make an untidy appearance.

This relatively stiff buckram or mesh band 16 going all around the crown of the hat gives a suitable shape to the same and a uniform contour thereto, and as the material itself is relatively thin, it does not add in any way to the bulkiness of the hat.

The material selected is buckram or mesh, so as to provide a large number of ventilating openings and so that there shall be a free passage of air through this ribbon 16.

Exterior of this band 16 a second band 18 is provided which is made of knitted silk, cotton, or the like, and which may have any color or design, the mesh of the knit being such as to provide a multiplicity of small ventilating openings, sufficiently small so as to be, preferably, not visible but large enough to provide efficient ventilation. 90

This band 18 resembles very closely a fine grade of ribbon as heretofore used, with the exception that it has a large number of ventilating openings, so that the appearance of this ventilating ribbon looks as if an ordinary band was applied to the hat. But here again, the multiplicity of openings gives a free ventilation from the exterior of the hat through the band 18, through the stiffening band 16, and through the ventilating openings 13 and 15. It will, therefore, be seen that with the large area openings in the hat, which large area openings are not materially constricted by reason of the ventilating openings of the band 16 and those of the band 18, a free circulation of air may take place through the outside and through the interior of the hat. Between the openings the hat portions which are not cut away from rigid supports 14.

In Fig. 5 another form of my improved hat is shown. In this embodiment the crown of the hat is made of two different weaves or braids. The upper part of the crown, as indicated by 27, as also the brim 28, is of the usual tight braid or weave. Interposed between the upper part of the crown and the brim, the lower part of the crown, as indicated by 29, is made of a different weave, namely, an open weave, so as to provide a large number of openings in the hat itself, which openings act as ventilating openings.

The sweat-band of the hat is provided with a large number of closely approaching ventilating openings 30, so as to have these openings 30 provide free ventilation through the sweat-band and through the ventilating openings of the hat itself.

Exterior to the crown of the hat the ventilated ribbon 31 hereinbefore described in connection with the ribbon 18 is provided. By the very large number of openings in the sweat-band, in the crown of the hat, and in the hat-band itself, a free circulation of air from the interior of the hat to the exterior thereof, and vice versa, is obtained.

In Fig. 6 I have shown an enlarged view of the lower part of the crown, showing the ventilating openings 32 formed by the braid or weave of the straw itself.

The ventilating openings or perforations in the sweat-band and hat can be readily stamped out by suitable machinery.

In each of the embodiments before described, the ventilation is so obtained as not to have the means for bringing about the circulation of air visible to the ordinary observer.

Various forms of ventilating devices have been proposed heretofore, but these have been so formed that they were visible at the exterior of the hat and, therefore, had the objection that immediately it could be seen that a special form of ventilated hat was being worn, which is objectionable to some users. In other forms of devices proposed, bulging portions of the ribbon or the sweat-band were provided which were disadvantageous in their use.

In my improved form, however, both the ribbon and the sweat-band closely approximate in appearance and in use the usual sweat-bands and ribbons as heretofore used, but are provided with the ventilating de-

vices heretofore described for insuring a proper circulation of the air.

My improved hat is of less weight than the ordinary hat; and also of less weight than some of the ventilated hats heretofore proposed.

I have shown various embodiments of my invention, but changes may be made therein without departing from the spirit of the invention.

What I claim as new and desire to secure by Letters Patent is:

1. An improved hat comprising, a crown having a plurality of openings therein arranged in the sides and in the front and back of the crown, said openings being large and being of a length greater than the spaces between the openings, the crown having upwardly arched upper marginal edges for the openings to reinforce the crown against crushing and compensate for the small portions of crown left between the long openings, a sweat band having a plurality of openings of substantially the same size and contour as the openings in the crown, a foraminous stiffening band exterior of the crown, and a foraminous hat band extending over said stiffening band at the exterior thereof.

2. An improved hat comprising, a crown having a plurality of openings therein arranged in the sides and in the front and back of the crown, said openings being large and being of a length greater than the spaces between the openings, the crown having upwardly arched upper marginal edges for the openings to reinforce the crown against crushing and compensate for the small portions of crown left between the long openings, a sweat band in the crown having openings therein corresponding in contour to those in the crown and registering therewith, said openings in the sweat band being slightly smaller than the openings in the crown to cover the marginal edges of the crown about said openings therein with the corresponding marginal edge portions of the sweat band, a foraminous stiffening band exterior of the crown, and a foraminous hat band extending over said stiffening band at the exterior thereof.

In testimony that I claim the foregoing as my invention, I have signed my name hereunder,

ANNA SOLOMON.
